AUTOMOBILE

Frederick Reynolds, Bloomfield Hills, and Herbert F. Weissinger, Franklin, Mich., assignors to Chrysler Corporation, Highland Park, Mich., a corporation of Delaware

Application May 11, 1955, Serial No. 35,932

Term of patent 14 years

(Cl. D14—3)

Fig. 1 is a perspective view from above and to one side of an automobile showing our new design with the side opposite being similar to the one illustrated;

Fig. 2 is a perspective view from the front thereof; and

Fig. 3 is a perspective view from the rear thereof.

The characteristic features of our design reside in the portions shown by means of full lines in the drawing.

We claim:

The ornamental design for an automobile, substantially as shown and described.
